UNITED STATES PATENT OFFICE.

TARGE G. MANDT, OF STOUGHTON, WISCONSIN.

THILL-COUPING.

SPECIFICATION forming part of Letters Patent No. 429,462, dated June 3, 1890.

Application filed March 7, 1890. Serial No. 342,989. (No model.)

To all whom it may concern:

Be it known that I, TARGE G. MANDT, a citizen of the United States, and a resident of Stoughton, in the county of Dane and State 5 of Wisconsin, have invented certain new and useful Improvements in Thill-Couplings; and I do hereby declare that the following is a full, clear, and exact description of the invention, which will enable others skilled in the 10 art to which it appertains to make and use the same, reference being had to the accompanying drawings, which form a part of this specification, and in which—

Figure 1 is a perspective view of my improved thill-coupling. Fig. 2 is a longitudinal sectional view of the same. Fig. 4 is a perspective view of the end of the thill-iron with its cross-head or coupling detached from the shackle. Fig. 3 is a perspective view of 20 the shackle, and Fig. 5 is a plan of the under side of the coupling.

Like letters of reference denote corresponding parts in all the figures.

This invention relates to thill-couplings or 25 shaft-couplings of the type known in the trade as "anti-rattlers;" and it consists in the improved construction and combination of parts of a device of that class, as will be hereinafter more fully described and claimed.

30 In the accompanying drawings, the letter A designates the thill proper, and B the thill-iron, the inner end of which is bent and shaped to form the cylindrical coupling-piece C and cross-head D. This cross-head, which 35 is in the nature of two reduced extensions of the cylindrical part C—one on each side—is provided at opposite ends with two downwardly-projecting tongues E, the straight side of which is recessed or notched, as shown at 40 F, for the purpose hereinafter set forth.

The shackle consists of two parallel side pieces G G, which, in connection with the cross-bars H and H', form a rectangular frame cast in one piece. The forward ends 45 of the sides G G are curved upwardly and recessed, as shown at I, to form bearings for the cross-head D, the ends of which rest in the recesses I, with the tongues E bearing against the outside of said recesses. The curved and 50 recessed bearings are provided with laterally-projecting lugs J, of such a size and shape that when the thill is in its normal position for draw-

ing the vehicle these lugs J will project into the triangular notches F in the side tongues E, and thereby interlock with the thill in such 55 a manner that this cannot possibly become detached on disconnected from its bearings in the shackle.

A slot K is cut in the forward shackle cross-bar H to form hinge-bearing for the spring-guard L. This consists of a flat piece of steel or other suitable metal, bent so as to form a curved cap or guard L, having an upward flap or projection L' and a tail-piece L'', which is inserted through the slot K and bent around 60 the rear part of cross-piece H to form a hinge. The back of the curved cap or guard L bears against the free end of a spring M, fastened to the rear part of the shackle-frame, between 65 said frame and the axle N, and projecting 70 with its free end up between the side pieces G G, as shown more clearly in Fig. 2 of the drawings. The cap or guard L is prevented from being forced too far forward, through the pressure of the spring M, by two studs N'— 75 one on each inner side of the curved couplings—above and integral with the forward cross-bar H, said studs or stops limiting the forward motion of the guard and its spring when the thill is detached or uncoupled from 80 the shackle. When the parts are coupled, however, the curved guard or cap L will bear against the cylindrical coupling-head C and operate to force the same firmly into its seat in the coupling, so as to prevent looseplay and consequent 85 rattling. This guard, actuated by the spring behind it, will also operate to take up wear by always seating the thill-head firmly in its recessed bearings in the shackle. In addition to this it serves as an auxiliary lock or fastening for the thill, which cannot be uncoupled or detached from the shackle except 90 by first drawing the guard back (by means of its projecting flap L') against the spring M, so as to release it from the cylindrical thill-head C and then raise the thill until the notched tongues E are disengaged from the interlocking fixed side lugs J, when the thill can readily be uncoupled from the shackle by simply lifting the coupling-head C D out of 95 100 the recessed bearings I I in the shackle.

The rectangular shackle body or frame G H H' is fastened to the under side of the axle N by two clips O O of the ordinary or com-

mon construction, and the shackle-spring M, projecting between said clips and the side pieces G G, is thereby held firmly in its place and effectually prevented from lateral dis- 5 placement.

Having thus described my invention, I claim and desire to secure by Letters Patent of the United States—

The combination, in a thill-coupling, of the 10 rectangular shackle-frame having the curved bearings I provided with the laterally-projecting and recessed lugs J, thill-iron B, having coupling-head or cross-head C D, provided with the downwardly-projecting tongues E, 15 adapted to engage the notched or recessed side lugs J, the cap or guard L, hinged in the forward cross-piece of the shackle-frame and

having the projection L', spring M, clamped between the rear cross-bar of the shackle-frame and the under side of the axle and projecting with its free end between the side bars of the shackle-frame and the clips, the clip O O, and the axle, all constructed and combined to operate substantially in the manner and for the purpose herein shown 20 25 and set forth.

In testimony that I claim the foregoing as my own I have hereunto affixed my signature in presence of two witnesses.

TARGE G. MANDT.
